ATTORNEY.

UNITED STATES PATENT OFFICE

2,136,745

SMOKING PIPE

Norman K. Jellinghaus, Philadelphia, Pa.

Application July 12, 1934, Serial No. 734,729
Renewed June 16, 1937

4 Claims. (Cl. 131—184)

My invention is a knife type cleaning device for smoking pipes. Such devices cleanse the bowl by a cutting or scraping action with the side or bottom walls or both. They have been generally 5 troublesome because lacking in practical form of cutting blade and practical means of operating them. My invention aims to eliminate both of these troubles and to constitute the device a practical machine in a true sense.

10 In the first place, I form the knife of high grade steel of relatively narrow blade form yet quite sharp but of generous cross section whereby the blade though stiff and sharp, through its narrowness conforms accurately to the carbon coated

15 walls with which it is supposed to coat. This section of blade I carry radially across the bottom wall of the bowl and then axially along the side walls of the bowl, forming the walls of the bowl cylindrically for this purpose.

20 In the second place, I provide means for rotating this knife comprising a shank projected axially through the bottom wall of the bowl, and I provide this shank with an axial elongation capable of being extended and collapsed to project an operating head thereof from the bottom of the bowl for convenient operation or to house that head within the general contour of the bottom of the bowl out of the way and out of side sight. This shank is journaled in a metallic bushing 25 itself fixedly threaded into the bottom of the bowl.

Thirdly, I improve the general draft conditions of the pipe by interconnecting the bowl and the stem through an annular orifice concentric with the rotatable shank of the cleaner and taking the place of the usual side or central orifice, particularly the central orifice, the position of which is now occupied by the shank of the cleaner. This orifice I form of a cross section the aggregate 30 area of which is substantially that of the draft orifice of the stem whereby the draft is distributed. A tine depended from the radial arm of the knife type cleaner projects into this orifice and when the cleaner is operated, cleans the orifice at the same time that the bowl is cleaned.

45 Referring to the accompanying drawing—
Figure 1 is an axial cross section of the bowl and stem in principal part showing a mounting for the knife type cleaner and the draft orifice in axial cross section along with the bowl and the stem.

50 Figure 2 is an axial cross section of the stem in the plane of transaxial cross section of the bottom

of the bowl taken substantially on line 2—2 of Fig. 1.

Figure 3 is a view of the bottom portion of the bowl particularly in axial cross section to display the elongation of the shank of the cleaner 5 to permit it to be manipulated.

Figure 4 is a view of the stem portion of the pipe and substantially in the same section but in perspective the better to portray the annular and circular form of the mounting and operating 10 parts of the cleaner and of the draft orifice, the shank of the cleaner being shown in collapsed form.

Figure 5 is a top plan view of the bowl.

Figures 6 and 7 are sections taken axially of 15 the bowl showing modifications of the structure of the bottom of the bowl.

The bowl is designated 10, the stem 11. The side walls of the bowl are designated 12, the bottom walls 13, and the stem orifice by 14. 20 This stem is of the form covered in my Patent No. 2,106,747, dated Feb. 1, 1938. It embodies a metallic barrel 15 the interior of which constitutes the stem orifice 14 and also the chamber of a piston type force pump. In Fig. 1 the piston 25 of this pump is designated 16 and the piston rod 17. So far as its relation to this case is concerned, suffice it to say that when the rod 17 (which is directly connected to the mouthpiece 18) is drawn from the stem 11, the piston 16 30 cleanses the chamber and orifice 14 of its condensed content.

The annular orifice 19 constitutes the sole and certainly the principal draft connection between the bowl 10 and the stem orifice 14. The annular 35 nature of this orifice can be clearly seen both in Figs. 4 and 5. Its bottommost portions 20 are somewhat enlarged in cross section and communicate directly with the stem orifice or chamber 14 by way of port 21 in the walls of the tube 40 15. The transaxial cross section of the orifice 19 at the bottom of the bowl, however, is constricted and is preferably not consequentially different from the cross section of the stem port 21, the relations of the cross sections, whether the same 45 or inconsequentially different, being such that the draft is annularly distributed substantially uniformly around the bottom of the bowl. A lesser orifice section is best.

50 This form and distribution of the draft aperture leaves the center of the bottom available for the mounting of the knife type cleaner. This mounting is in the form of a bushing 22 externally shouldered at its upper end and internally shouldered at its lower end. The bushing is 55

threaded axially through the bottom of the bowl from the inside in such manner that its external shoulder abuts a portion of the bottom wall and fixes it in axial position. Within this bushing 5 22 is journaled an axially extensible shank 23 for the knife type cleaner. This shank at its upper end is provided with an external shoulder and its lower end with an operating head 24 whereby it may be turned. The shank is assembled 10 into the bushing from its open upper end and the lower end of the shank projects through the lower end of the bushing where head 24 is joined thereto by pin connection 25 permitting easy placement and removal for assembly 15 and dis-assembly.

Journaled in the upper end of the bushing 22 is a knife type cleaner 26. The shank 27 of this cleaner is angular and is fitted slidably in a complementary angular socket 28 of the bushing 20 shank 23 whereby rotation of the shank 23 rotates the knife 26. The knife 26 is also journaled in the upper end of bushing 22. This journaling is by means of a journal bushing 29 threaded into the shouldered upper end of the bushing 22 25 and carrying the revolving journal bearing 30 (see Figs. 1, 4 and 5) fitted on to the angular knife shank 27 (see Figs. 2 and 3). Shank 27, bushing 29 and journal 30 are constituted a unit by a confining washer or spring 31 force fitted 30 around the angular shank 27 and abutting by its margins the lower end of the bushing 29. Thus these three parts, the knife 26, the bearing 29 and journal 30, may be applied to and removed from bushing 22 as a unit by threading bushing 35 29 into and out of the upper end of bushing 22. To facilitate this assembly the bushing 29 is provided with sockets 32 for a small spanner wrench.

The knife 26 is comprised of radial portions 33 40 radially traversing the bottom wall 13 and an integral axial portion 34 coacting with the carbon coated side walls 12 of the bowl. The shank 27 and the portions 33 and 34 are an integral piece of right angular formation of the general configuration of the letter Z. The portions 33 45 and 34 however are not of regular polygonal form but are of flattened polygonal form generally trapezoidal as clearly appears in Figs. 4 and 5. The opposed edges are beveled and sharp. The blade is relatively narrow readily conforming 50 therefore to the large curvature of the side walls of the bowl 12. Yet the general cross section is stocky and the blade as formed of high grade steel quite stiff.

The under side of the radial portion 33 of 55 the blade is provided with the tine 35 which projects into the annular orifice 19 and to a sufficient depth therein to thoroughly cleanse the aperture when the cleaner 34 is rotated. Indeed, this depth is such that tine 35 reaches into 60 the port 21 by which the annular orifice 19 communicates with the stem orifice 14, whereby it may also cleanse this port. To this end orifice 19 overlies port 21 and the side walls of port 21 are cut away in such fashion as to permit tine 65 35 to rotate therethrough when the knife 26 is turned. To facilitate the formation of orifice 19 and to afford it the difference of cross section between its bottom 20 and its upper end, the bottom wall 13 of the bowl is constituted jointly 70 by the flush upper faces 36 (see Fig. 5) of the bushing and journal 29—30 and of a surrounding ring 37. This ring 37 fits closely around the upper end of bushing 22, is at its upper face flush with the faces 36 of members 29 and 30, and 75 has an outer periphery of a dimension which

properly constricts the orifice 19. The bushing 29 is shouldered at its upper end to abut the upper end of the bushing 22 and also to project therebeyond and bear upon the ring 37 to retain the same in place about the bushing 22. 5 Ring 37 is also threaded and pinned to the upper end of bushing 22.

The operation of smoking consists merely in filling the pipe, packing to any extent desired, and lighting and smoking it by drawing through 10 the aperture 19. The draw is uniformly distributed and the smoking excellent all the way to the bottom of the charge. The smoke complete, one grasps the head 24 by the thumb and forefinger, extends it from the position in Fig. 1 to 15 the position in Fig. 3, and rotates it one or two complete revolutions, thereby loosening the residue of the charge, whereupon the residue may be freely dumped.

The act of cleansing the bowl of residue not 20 only scrapes the side walls of the bowl to an extent permitting the determinate carbon residue desired, but also by the action of tine 35 cleanses the orifice 19 from which the removed material passes into the port 21 and from which latter 25 residue and condensation is removed by the pump plunger 16. The knife 26 when the pipe is new preferably lies a determinate distance from the side wall 12, such for example, as the distance 38 30 whereby the bowl is coated with carbon or caked, as is commonly said, to a depth of a small fraction of an inch before the knife begins actually to 35 scrape the side walls of the bowl. After the carbon caking has proceeded to this depth, the knife will accurately maintain the bowl of uniform open diameter.

Figure 6 shows the structure wherein the ring 37 is integral with the bushing 22. Figure 7 shows the construction where the ring 37 is integral with the bowl 10. In this instance the bowl 40 cleaner is illustrated without a stem ejector. In such case the stem orifice 14 is drilled through part-way into the ring 37 whereby a pipe cleaner may transect the annular orifice 19 cleansing it perfectly at this point. The tine 35 similarly 45 transects the orifice 14 and for the same purpose.

Many modifications may be made without departing in any wise from the generic spirit of my invention and these modifications should be protected to me by the appended claims. 50

What I claim as new and useful and desire to protect by Letters Patent is:—

1. In a smoking pipe, a bowl, a cleaner knife coacting with the side walls of the bowl and means to rotate the knife journaled axially of the 55 bottom of the bowl and comprising an axially elongatable shank terminating in an external actuating head, which head is normally housed within the bottom general contour of the pipe but when the shank is elongated is projected there- 60 beyond for freedom of operation.

2. In a pipe, a bowl, a stem, an annular orifice in the bottom of the bowl in open communication with the stem, a movable bowl cleaner and orifice cleaning means carried by the bowl cleaner to 65 thoroughly clean opposed walls of the orifice.

3. In a pipe, a bowl, a stem, an annular orifice in the bottom of the bowl constituting means of communication between the bowl and the stem, a rotary knife type bowl cleaner and a tine carried by the knife and projecting into the annular orifice to thoroughly clean opposed walls thereof at the same time the cleaner is rotated to clean the bowl. 70

4. In a pipe, a bowl, a bushing having its upper 75

end externally shouldered and its lower end internally shouldered, threaded axially into the bottom of the bowl from the inside thereof to abut the bottom wall by its external shoulder, an externally shouldered shank journaled in said bushing to project out of the lower end thereof with its shoulder abutting the internal shoulder of the bushing, a knife type bowl cleaner jour-

naled in the upper end of said bushing and having a shank coupled to the said bushing shank in axial extensible relation, and means to retain the shouldered shank in the bushing and the knife shank in the shouldered shank against axial dislodgment. 5
